MAGNETIC GAME BOARD AND COVER THEREFOR

Filed Aug. 30, 1945

UNITED STATES PATENT OFFICE

2,511,774

MAGNETIC GAME BOARD AND COVER
THEREFOR

Robert H. Goldsmith, New York, N. Y.

Application August 30, 1945, Serial No. 613,492

6 Claims. (CL. 273—136)

1

This invention relates to game boards, especially suited for use by travelers, and is herein disclosed in some detail as embodied in a structure in which the playing board surface forms part of a light box, provided with drawers for holding the men or pieces used in playing the game, and provided with holding devices which may take the form of magnetic units for holding the men when placed upon the squares or other divisions of the board surface.

Attempts have been made in the past to provide small game boards convenient for travelers, or for use by an invalid, but the boards have proved unsatisfactory. Some of these boards were made of thick wood with holes bored centrally of the squares so that pegs on the bases of the playing pieces could be thrust into the holes and thus hold a played piece where set, but the device was bulky, the movements of a player's hand in moving a piece seemed unnatural and awkward.

Other boards included a flat pocket at each square so that a tab on a playing piece could be fitted into the pocket to hold the piece, the piece usually being a flat form of cardboard printed to resemble a standard type of playing piece.

It has been also proposed to provide playing pieces carrying magnets embedded in them, on the assumption that the minute magnets would hold the pieces to a magnetic metal playing board wherever placed.

Except for the board provided with pockets and pegs all these prior boards exercised such a weak hold upon the pieces that the pieces became displaced when the board was shaken or tilted, and so were found unreliable, when the board was set aside by interruption of the game, and it was later attempted to go on with the game on the assumption that the pieces remained in their set positions.

According to the present invention the foregoing and other difficulties and objections are overcome and a game board is provided in which a magnet forms part of each square of the board, and is effective on magnetic units carried by the pieces. Thus the magnets tend to center the pieces in the squares of the board.

This makes it possible to apply a cover to the board partitioned off so as to hold each playing piece in its set position. Thus the pieces are ready to continue a game which was interrupted assured that the pieces have remained undisturbed.

The drawers for holding the playing pieces may occupy any desired position, preferably below the surface of the board and withdrawable at the ends of the board.

The cover may take the form of an arched sheet of plastic extending completely over the

2

board and covering the ends of the drawers and carry the partitions on its lower face so that they serve as stiffening girders enabling the cover to be formed of exceedingly light material.

5 The body of the board is advantageously made from synthetic plastic, and the playing face may have a transparent sheet, such as "lumarith," "cellophane," "celluloid," or other transparent material adapted to take paint or ink on its under side, thus making it impossible for the colors of squares to be worn off when the marking off of squares is on the under side of the plastic sheet.

10 One object of the invention is to provide a convenient compact playing board.

Another object of the invention is to provide a small sized playing board for reliably holding playing pieces.

Another object of the invention is to provide a cover with positive means for holding playing pieces in their played position.

Another object of the invention is to provide a board in which playing pieces are held against ordinary jolting.

25 Another object of the invention is to provide an automatic closing receptacle for pieces not in use.

Another object of the invention is to provide a compact complete unitary playing board and playing piece holding device.

Another object of the invention is to provide a board the pattern of which is unmarred by holes, exposed metals or other appurtenances.

30 Another object of the invention is to furnish a cover which may remain in removable combination with the playing board when the playing surface is uncovered.

Other and further objects of the invention will be obvious upon an understanding of the illustrative embodiment about to be described, or will be indicated in the appended claims, and various advantages not referred to herein will occur to one skilled in the art upon employment of the invention in practice.

45 A preferred embodiment of the invention has been chosen for purposes of illustration and description and is shown in the accompanying drawings, forming a part of the specification, wherein

Fig. 1 is a top plan view of one form of the invention with certain parts broken away;

Fig. 2 is a section side view on the broken line 2—2;

50 Fig. 3 is a sectional end view on the broken line 3—3;

Fig. 4 is a similar view on the line 4—4;

Fig. 5 is a perspective view of the closed board;

Fig. 6 is a fragmentary plan view of the board

60 with the top cover removed;

Fig. 7 is a side view of a man for playing checkers;

Fig. 8 is a side view of a man for playing chess; and

Fig. 9 shows an alternative form of chess man with a magnetized core.

In the form shown the board structure includes a plastic base board 10 which is shown as molded in the form of a thick sheet having a bore or cylindrical opening 11 below each square 12 of 10 the playing surface 13.

Each bore 11 is shown as carrying a closely fitting, glued in, or otherwise bonded to the base, cylindrical permanent magnet 14 which is often satisfactory if a piece of magnetized steel but 15 may hold more strongly if made of one of the highly magnetizable special alloys. The magnets 14 are preferably all set with the same pole up and about three eighths of an inch long and three sixteenths of an inch in diameter.

The board shown for convenience is a checker board with eight squares on each side, and the magnets 14 are adapted to hold checker men 15 by magnetizable cores 16 in the men 15. The cores 16 also serve to magnetically hold superimposed checkers in place when a checker is crowned.

Where the men 15 are adapted to be used either end up, the core 16 may be made of soft iron so that either end of the core is equally effective.

When chess men 17 are used, which are always played the same end up, the core 18 may take the form of a flat hard steel magnetized bottom 19 for the man, which is magnetized so that all the chess men present the same pole to the magnets 14, and if the magnets are set north end up, all the chess men bottoms 19 are magnetized with north end up. For use in locations where vibration is great or violent, the bottoms 19 may be of a special highly magnetized alloy. In Fig. 9 is shown a core 19a which may be a polarized magnet, within a chess man.

It is found, however, that steel magnets 14 are magnetizable sufficiently for ordinary purposes to hold the cores 16 without resorting to the highly magnetizable alloy.

The cover 21 shown may be a thin sheet of synthetic plastic having downwardly curved edges 22 that rest on a peripheral bottom ledge 23 that runs around the bottom of the plastic base board 10, so that the inner faces of the curved edges 22 fit snugly against the periphery 24 of the board and are firmly supported. Thus a very thin and light cover is of ample strength.

In the form shown the cover 21 carries cross-bars 25 on the inner surface of its top, and the cross-bars in the form shown, are adapted to rest just clear of the dividing lines between the squares 12, and are cemented to or molded integrally with the cover 21. Thus it comes about that cross-bars 25 lie around any playing piece 15 or 17 which may be standing on any square 12, and hold it against being displaced while the cover is on.

To utilize this holding of playing pieces the cross-bars 25 are only slightly deeper than the highest chess man, or than the height of two superposed checker men which are called a king.

The cover 21 carries, for this purpose, not only a cross-bar 25 for the dividing line between every two squares 12, but also carries a cross-bar 25 at each margin of the outer squares 12.

By using playing pieces 15, 17 which are more than half the width of a square 12 and of a satisfactory height the best results are obtained.

and an uninterrupted game setting is perfectly preserved, ready for resuming, by placing the cover 21 down on the board so that its cross-bars 25 of satisfactory width hold the men in place until the cover is removed. The magnets 14 hold the men while the cover is being removed even if the board is somewhat shaken.

To allow for slight deviation from position of chess or checker men when cover is applied the faces of each cross-bar 25 are beveled adjacent to the periphery of each square 12, thereby forming a wedge shaped end which slides the character into centered position during the closing operation.

The cover 21 may be held in place by any suitable device. In the form shown, the cover 21 carries, centrally on two opposite ends, a pair of latches 26 having hooks 27 adapted to enter undercut openings 28 in the plastic base board as they swing on pivots 29 mounted on internal ears 30 fastened to the cover.

In the form shown the latches 26 are provided with outer faces 31 which lie flush with the curved surface that ends in the edge 22, and include cam faces 32 adapted to cam the hooks 27 outward as the cover 21 is pushed down. When the hooks 27 have been swung out by the cams to slip down the end of the board, they catch in the openings 28 because they are spring-pressed into engagement by light springs 30b, but are easily released by pressing at the outer surface 32a of the latch at depressions 33a near their extensions 30a that hold them against overthrow.

It is convenient to keep the men in a receptacle with the board, and in the form shown, the board carries slidable drawers 33 which may slide under the magnets, if desired, but are shown as sliding inside extensions 34 of the plastic base board 10, so that the extensions 37 give a hand rest, and the board 10 is a little thicker than the length of the magnets 14.

In the form shown the squares 12 are painted on the back of a thin sheet 35 of transparent plastic such as "cellophane" or "celluloid" film. Thus the rulings and colors of the squares 12 can never become worn. The playing surface formed by the squares 12, lies in the open central face of the overlying molding or strips 36 which may be molded from a single piece of plastic, preferably opaque, which serves to protect the edges of sheet 35 and also to act as a central portion for extensions 37.

The strips 36 may broaden into plates 37 over the drawers 33, and serve as covers for the drawers 33.

The thin sheet 35 and the integral squares 12 are cemented by glue or other material 20 to the smooth surface afforded by the tops of all the magnets 14 and the top of the plastic base board 10.

In the form shown the open topped drawers 33 are molded from plastic so as to be thin walled and yet strong and with enough clearance to accommodate the playing pieces.

In the form shown there are four drawers 33, one in each half of each extension 37, and they are each held closed because each is connected by a long spiral spring 38 and cord 39 to the facing drawer 33 at the opposite end of the board 10, each spring lying in a bore 40 in the body of the board 10, and located along a dividing line of squares 12, so that it lies between magnets 14.

Cord 39 is continuous between opposite pairs of drawers, being knotted to both ends of the spiral spring 38 and passing through the spiral spring

38. The portion of the cord 39 passing through the center 39a of the spiral spring 38 possesses a sufficient length of slack to limit the degree of opening of one drawer. This degree of opening may be such as to permit the drawer to be canted in a horizontal plane when in open position so that it will remain open, thereby facilitating removing or replacing of characters.

The length of cord is such that only one of each opposite pair of drawers may be fully opened to the desired degree at one time. Hence the two drawers containing chess men are located diagonal to one another on opposite sides of the board and similarly for the two drawers containing checker men. The cord may be knotted inside the end of one drawer and pass through the end of the other drawer as at 44 and be clamped within the drawer by any suitable clamp (not shown).

The cover 21 may include symmetrically placed lugs 41 adapted to fit in corresponding openings 42 in the peripheral ledge 21, thus making it possible to invert the cover and fit it upside down on the bottom of the plastic base 10.

The drawers 33 shown include higher fronts 43 which limit the pull of a drawer 33 inward by its spring 38.

Notches 37a in the edge of the extension 37 make it possible to easily pull out the drawer 33.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. The combination of a generally planar sheet having a surface marked into squares, a baseboard supporting said sheet, and having a socket underlying each square, a magnet in each socket adapted to magnetically hold to the sheet a playing piece embodying a magnetic substance, a cover conforming generally in shape and size to that of said baseboard adapted to overlie the baseboard and having edges fitting down over edges of the baseboard, and dividing members intersecting each other extending downwardly from the inner surface of the cover and forming squares conforming generally to those of said sheet adapted to fit between playing pieces on said sheet to hold them against displacement.

2. In a device of the class described, the combination of a game-playing board having marginally disposed lug-receiving openings, a cover selectively fittable over upper and lower surfaces of the game board having edge walls projecting downwardly, and lugs projecting downwardly from said edge walls adapted to fit into said lug-receiving openings in the game board, so that the lugs of the cover fit the openings when used as an upper cover and the lugs fit the openings when the cover is inverted to fit under the board.

3. In a device of the class described, the combination of a game-playing board, an outwardly projecting ledge around the game board including a plurality of lug-receiving openings extending therethrough, a cover for the game board selectively fittable over top and bottom surfaces of said board having skirt-like edge walls to rest at their lower ends on the ledge, and a plurality of lugs on the skirt-like edge walls to fit in the lug-receiving openings when used as a cover and adapted to fit in the lug-receiving openings when inverted and placed against the bottom of the board.

4. In a device of the class described, the combination with a game-playing board having a game-playing surface, of a cover for the game board selectively fittable over top and bottom surfaces of the board having a plurality of vertical partitions located within an area corresponding to said game-playing surface forming a plurality of open-ended chambers adapted to hold playing pieces in set positions on the game-playing surface of the game board, downwardly projecting edge walls on the cover, a ledge on the board on which said edge walls of the cover may rest having lug-receiving openings, lugs on the edge walls of the cover adapted to fit in openings in the ledge of the board, whereby the cover may be inverted and lugs thereon fitted in the openings of said ledge.

5. The combination of a generally planar sheet having a surface marked into a plurality of divisions, a baseboard member supporting said sheet, a cover member conforming generally in shape and size to that of said baseboard adapted to overlie the baseboard, one of said members having portions fitting along portions of the other member, and intersecting dividing means extending downwardly from the inner surface of the cover member and forming divisions conforming generally to those of said sheet and adapted to fit between playing pieces on said sheet to hold them against displacement.

6. The combination of a generally planar sheet having a surface marked into a plurality of divisions, a baseboard member supporting said sheet, and having a recess underlying each division, a magnet in each recess adapted to magnetically hold to the sheet a playing piece embodying a magnetic substance, a cover member conforming generally in shape and size to that of said baseboard adapted to overlie the baseboard, one of said members having portions fitting along portions of the other member, and intersecting dividing means extending downwardly from the inner surface of the cover member and forming divisions conforming generally to those of said sheet and adapted to fit between playing pieces on said sheet to hold them against displacement.
